(57) **CLAIM**

The ornamental design for an espresso glass with saucer, as shown and described.

DESCRIPTION

FIG. 1 is a top perspective view of an espresso glass with saucer showing my new design;

FIG. 2 is a bottom perspective view thereof;

FIG. 3 is a top plan view thereof in a reduced scale;

FIG. 4 is a front elevational view thereof in a reduced scale; all sides being the same;

FIG. 5 is a bottom plan view thereof in a reduced scale;

FIG. 6 is a cross-sectional view thereof taken along section

6-6 of FIG. 4; and,

FIG. 7 is an exploded top perspective view thereof.

1 Claim, 5 Drawing Sheets(56)
